UNITED STATES PATENT OFFICE.

EDWARD H. BELDEN, OF TOLEDO, OHIO, ASSIGNOR, BY MESNE ASSIGNMENTS, TO THE WILLYS-OVERLAND COMPANY, OF TOLEDO, OHIO, A CORPORATION OF OHIO.

LUBRICATION SYSTEM FOR INTERNAL-COMBUSTION ENGINES.

Application filed October 1, 1917. Serial No. 194,182.

This invention relates to improvements in lubricating systems for internal combustion engines.

The principal object of my invention is to provide a lubrication system in which the oil is fed by gravity from an oil reservoir through suitable passages to the bearings which are to be lubricated, said system having simple and effective means whereby the 5 rotating fly-wheel of the engine lifts the lubricating oil from the lower part of the crank case to the reservoir, said oil being diverted and directed from the fly-wheel casing into the oil reservoir by means of a 10 15 suitably disposed baffle.

A further object of my invention is to provide a simple and convenient arrangement by which the upper part of the fly-wheel casing, the oil reservoir and the upper 20 25 half of the forward crank shaft bearing are formed integrally, said oil reservoir and fly-wheel casing and said reservoir and bearing being connected by suitable ports and passages.

25 A further object of my invention is to provide a simple and effective means for securely holding a strainer in place in said oil reservoir and at the same time holding the cover in place over said reservoir.

30 Further objects, and objects relating to economies of manufacture and details of construction, will definitely appear from the detailed description to follow:

I accomplish the objects of my invention 35 by the devices and means described in the following specifications.

A structure constituting a preferred embodiment of my invention is illustrated in the accompanying drawings, forming a part 40 of this specification, in which:

Figure I is a view in side elevation of the rear end of an engine, embodying my invention.

Figure II is a top plan view of the engine 45 shown in Figure I.

Figure III is a detail, fragmentary, sectional view, taken substantially on the line III-III of Figure I.

Figure IV is a fragmentary, detail, sectional view, taken substantially on the line IV-IV of Figure I.

Figure V is a detail, sectional view, taken substantially on the line V-V of Figure II, and

Figure VI is a top plan view of the oil

reservoir with the cover removed, taken substantially on the line VI-VI of Figure V.

In the drawings, similar reference numerals refer to similar parts throughout the several views and the sectional views are 60 taken looking in the direction of the little arrows at the ends of the section lines.

Considering the numbered parts of the drawing, I have shown an engine comprising a crank case made up of the lower half 10 65 and the upper half 11, on which the cylinder block 12 is mounted. The crank shaft 14 is journaled in the crank case in the usual manner and the fly-wheel 15 is secured to the rear end of the crank shaft, the lower 70 half of said fly-wheel being disposed within the crank case 10 while its upper half is disposed within the fly-wheel casing 13 as shown in Figure I. A partition 16 in the lower half of the crank case 10 divides the 75 portion of the crank case in which the fly-wheel turns from the rest of said crank case and aids in supporting an oil pan 17. The upper wall of the fly-wheel casing 13 is formed with a downwardly extending flange 80 18, and the wall of the fly-wheel casing adjacent said flange is inclined upwardly at 19 so that said flange 18 and said wall 19 form a baffle so that the lubricating oil carried upwardly by the fly-wheel as it turns is directed by the baffle through the port 21 which communicates with the oil reservoir 20 formed integral with the fly-wheel casing 13.

The reservoir 20 has a well 22 in which 90 is disposed a strainer 23 open at its upper end and carried by a ring 24 which rests on a rubber gasket 25 disposed on the annular shoulder 26 at the top of the well 22. A spider is provided, having a plurality of 95 arms 27, of spring material, extending downwardly and laterally from the center of said spider, and each having a foot 28 which rests on the ring 24. The center of the spider is provided with a concave depression 29 and the arrangement of this spider is clearly shown in Figures V and VI. A cover 30 closes the open upper end of the oil reservoir 20 and is provided with a concave depression 31, which engages the depression 29 of the spider. The cover 30 rests 100 on the gasket 32 on the top of the reservoir. A bar 33 extends across the top of the reservoir and is provided with downturned ends having laterally extending lugs 34 which

110

engage beneath the flange 35 at the top of the reservoir. A screw 36 is threaded in the bar 33 and engages the depression 31 in the cover.

5 An integral extension 37 extends laterally from the reservoir 20 and has a passage 38 therein, which communicates with the well 22 through a port 39. Passage 38 connects with a passage 40 which extends longitudinally of the engine and delivers lubricating oil to the various bearings in a manner well understood in the art. At the end of the extension 37 there is formed a half-round bearing 41 for the crank shaft 14, which 10 operates with a mating member, forming part of the lower crank case 10, and is secured thereto by bolts threaded into the threaded openings 42. A passage 43 connects with the passage 38 so that lubricant 15 is delivered from the reservoir 20 through the passages 39, 38 and 43 to the forward crank shaft bearing.

From the description of the parts given above, the operation should be very readily understood. Lubricating oil is continuously 20 delivered by gravity from the well 22 through the passages 39, 40, 38 and 43 to the various bearings of the engine in a manner well understood in the art. The supply of oil in the reservoir 20 is maintained 25 by the action of the baffle comprised by the flange 18 and the upwardly inclined wall 19. The lower part of the fly-wheel is disposed 30 in the lubricating oil contained in the base of the crank case and, as said fly-wheel rotates when the engine is running, part of this oil will be carried up with the fly-wheel and such oil being thrown against the top 35 of the fly-wheel casing 13, the baffle, made up of the flange 18 and the wall 19, will direct a portion of this oil from the fly-wheel casing through the port 21 into the well 22 of the oil reservoir 20, from which 40 it will feed by gravity to the various bearings in the usual manner.

As the oil is thrown upwardly by the fly-wheel the centrifugal force imparted to the oil throws it against the baffle plate with considerable force and the oil is therefore 45 forced into the reservoir under considerable pressure which aids in feeding the oil through the strainer and the various passages to the bearings.

The passage 21 leading from the fly wheel 50 chamber into reservoir 20 is of sufficient size to accommodate the greatest flow of oil which the apparatus is capable of passing between flange 18 and inclined wall 19, constituting the deflecting baffle, and without 55 interposing any obstruction to such flow. The passage 21 has no constriction in it and is not to be understood as a constricted passage. The force with which the oil enters reservoir 20 is due entirely to the centrifugal 60 action of the fly wheel as distinguished from

force which it would be possible to exert by constricting passage 21 in a manner similar to that illustrated in my Patent 1,508,914 issued Sept. 16, 1924.

The cover 30 is held on the top of the 70 reservoir 20 and the strainer 23 is held in position in said reservoir by the screw 36 which co-operates with the bar 33 and the cover 30. By loosening the screw 36, the bar 33 can be removed and the cover 30 can then 75 be taken off and the spider and strainer ring 24 with the strainer 23 can be removed so as to clean the strainer, if such becomes necessary. When the screw 36 is screwed down it puts a pressure on the cover 30 to clamp 80 the cover in place and this pressure is transmitted through the yielding arm 27 of the spider to the strainer ring so as to seat both the cover and the strainer ring firmly in place.

85 I am aware that the particular embodiment of my invention, which I have here shown and described, is susceptible of considerable variation without departing from the spirit thereof, and, therefore, I desire 90 to claim the same broadly, as well as specifically, as indicated by the appended claims.

Having thus described my invention, what I claim as new and desire to secure by Letters Patent, is:

1. In an internal combustion engine, the combination of a crank-case, a crank-shaft journaled therein, a fly-wheel on said crank-shaft, an integral member comprising in 100 part a casing for said fly-wheel and a bearing for said shaft and forming an oil reservoir having a passage leading to said casing and having a passage leading to said bearing, and a baffle whereby oil thrown 105 from said fly-wheel is directed into said reservoir and from thence to said bearing.

2. In an internal combustion engine, the combination of a casing for the engine fly-wheel, an oil reservoir, a passage connecting said casing and said reservoir, a baffle disposed to direct oil carried up by said fly-wheel through said passage, oil passages connecting said reservoir with the bearings to be lubricated, a strainer disposed in said reservoir and including a strainer ring seated on an annular shoulder formed in said reservoir, a cover for said reservoir, and a single means for clamping said cover and said strainer ring in place.

3. In an internal combustion engine, the combination of an oil reservoir, oil passages connecting said reservoir with the bearings to be lubricated, said reservoir being provided with an internal shoulder therein, a ring seated thereon, a strainer carried by said ring, a spider having downwardly and laterally extending arms engaging said ring, a cover closing the upper end of said reservoir and engaging the central part of 120 125 130

said spider, and fastening means engaging the central part of said cover for clamping the same in place on said reservoir.

4. In an internal combustion engine, the combination of a crank-case, a crank-shaft and fly-wheel journaled therein, said crank-case comprising a fly-wheel housing, an oil reservoir and a crank-shaft bearing, said parts being formed integrally with each other and having a passage formed therein connecting the reservoir and the fly-wheel housing and another passage connecting the reservoir and the crank-shaft bearing, and a baffle in said housing disposed to direct oil carried up by said fly-wheel into said first passage.

5. In a lubricating system for engines, a casing, a rotating element within the casing adapted to carry oil upwardly from the lower portion thereof, a baffle extending transversely of the casing and having one

end farther advanced circumferentially of the rotating element than the other, and an oil line having its receiving end connected to the interior of the casing adjacent said farther-advanced end of the baffle, said baffle being adapted to deflect lubricant and, in co-operation with said rotating element, to force said lubricant from the farther-advanced end of the baffle into the oil line. 25

6. In a lubricating system for engines, a casing, a rotating element mounted on a horizontal axis within the casing, and a baffle extending transversely of the casing and having one end further advanced circumferentially of the rotating element than the other, said baffle being positioned on the up-going side of said rotating element, so as to receive oil thrown therefrom by centrifugal force and to deflect it sidewise. 30 35

In testimony whereof I affix my signature.
EDWARD H. BELDEN.
